UNITED STATES PATENT OFFICE.

GRANT A. WALLER AND FLOYD E. WRIGHT, OF FORTVILLE, INDIANA, ASSIGNEES TO
QUINCY A. WRIGHT AND FLOYD E. WRIGHT, BOTH OF FORTVILLE, INDIANA.

ACETYLENE-GAS GENERATOR.

1,109,377.

Specification of Letters Patent.

Patented Sept. 1, 1914.

Application filed May 3, 1912. Serial No. 694,843.

To all whom it may concern:

Be it known that we, GRANT A. WALLER and FLOYD E. WRIGHT, citizens of the United States, residing at Fortville, in the 5 county of Hancock and State of Indiana, have invented a new and useful Acetylene-Gas Generator, of which the following is a specification, reference being had to the accompanying drawings and to the letters and 10 figures of reference marked thereon.

This invention relates to the type of apparatus that is designed to generate acetylene gas for use in buildings and maintain a supply of gas sufficient at all times for 15 present needs, the invention having reference more particularly to apparatus for automatically feeding carbid into water for generating the gas.

An object of the invention is to provide 20 an improved acetylene gas generator of such construction as to be adapted to be conveniently shipped from factories without being liable to be damaged in transit and which shall not be liable to derangement in use.

25 An important object is to provide a simply constructed carbid feeder which shall be reliable in operation.

A still further object is to provide a gas 30 generator of the above mentioned character that shall be so constructed as to be conveniently recharged with carbid and also with water, especially when holding gas, and which will permit the residuum to be conveniently removed from the generating 35 tank.

With the above mentioned and other objects in view, the invention consists in an acetylene gas generator comprising a generating tank, a gas-bell, and an improved carbid magazine and feed-apparatus.

The invention consists also in the novel parts and in the combinations and arrangements of parts as hereinafter particularly described and claimed.

40 Referring to the drawings, Figure 1 is a front elevation of the improved gas generator partially broken away; Fig. 2, a vertical section on the plane of the line A A in Fig. 1; Fig. 3, a top plan of the generating tank and appurtenances thereof; Fig. 4, a fragmentary section on the plane of the line B B in Fig. 3; Fig. 5, a fragmentary section on the plane of the line C C in Fig. 3; Fig. 6, a fragmentary section on the line D D 45 in Fig. 2; Fig. 7, a section of the feeding

apparatus on the line E E in Fig. 2; Fig. 8, a section on the plane of the line F F in Fig. 7; Fig. 9, a fragmentary section on the plane of the line G G in Fig. 3; Fig. 10, a fragmentary section on the plane at right angles to the line A A; Fig. 11, a fragmentary section approximately on the line H H in Fig. 4, and Fig. 12, a fragmentary section of the tank and sealing compartment.

Similar reference characters throughout 60 the drawings indicate like elements or features of construction in the different figures thereof.

A suitable generating tank comprises a bottom 1 on which is a cylindrical side wall 2, a cylindrical casing 3 somewhat greater in diameter than the wall 2 extending about the latter from a plane above the bottom 1 to a plane beyond the normally upper end of the tank, the casing having an annular 70 bottom 4 which extends about the wall 2 and is secured thereto, all being composed of galvanized iron permitting soldered joints, the wall 2 and the case 3 with its bottom constituting an annular sealing compartment capable of holding water or other sealing liquid, and the bottom 1 is provided with a suitable drain cock 5. The lower portion of the wall 2 adjacent to the bottom 1 is provided with a drain cock 6 75 through which the foul water and residuum may escape. A tube 7 is secured vertically to the exterior of the casing 3 and extends downward substantially to the plane of the bottom 1 and has a box 8 on its lower end 80 which is relatively broad horizontally and which is secured in a suitable opening in the wall 2. The tube extends upward a suitable distance and has a funnel 9 on its upper end, the tube being provided with an overflow 85 spout 10 arranged at a suitable height to permit the water to flow out from the tank when the level of the water rises above the desired height due to deposits of the carbid 90 in the tank. A guide 11 is preferably secured to the casing 3 within the funnel 9 and a rod 12 extends through the guide and downward in the tube 7 and has a handle 13 on its upper end, the lower end of the rod having an arm 14 thereon extending 95 through the box 8, the arm having a suitable stirring and scraping blade 15 thereon which is adapted to be moved across the bottom 1 of the tank in order to loosen the residuum so that it may flow out with the 100

105

110

foul water. The water may be poured into the funnel 9 in order to replenish the tank with water for slaking the carbid. A portion of the wall 2 adjacent to the bottom 1 has a vertical slot 16 therein which is covered by a box 17 secured to the exterior of the wall, the box having a neck portion 18 thereon extending upward a suitable distance and secured to the exterior of the casing 3, the upper end of the neck preferably having a funnel 19 thereon. A guide 20 is secured to the casing 3 within the funnel and a guide 21 is secured to the inner side of the wall 2. A rod 22 extends through the guide 20 and has a handle 23 on its upper end which when desired may be supported on an arm 24 that is pivotally supported in a bracket 25 secured to the casing 3, and the rod may be lowered when the arm is swung away from beneath the handle. The normally lower end of the rod 22 has a lateral arm 26 thereon within the box 17 and a return rod 27 extends from the arm upward through the guide 21 and has a cross-bar 28 thereon which is provided with a downwardly extending finger 29 which is in contact with the inner side of the wall 2 behind a vertical guide 30 on the wall. The slaking water may if desired be poured also into the funnel 19, or the funnel may receive water for washing out the residuum from the tank.

The upper portion of the casing 3 has an aperture 31 therein provided with a funnel 32 in order that the sealing water or liquid may be conveniently poured into the sealing compartment. An outlet pipe 33 is arranged adjacent to the inner side of the wall 2 and is supported on an elbow 34 which is connected to a discharge pipe 35 extending through and secured to the wall, the upper end of the pipe 33 preferably having an elbow 36 thereon to prevent moisture from entering the outlet pipe with the gas.

The generator is provided with a safety-valve which comprises an upright pipe 37 supported by an elbow 38 adjacent to the inner side of the wall 2, the elbow being connected to and supported by an escape pipe 39 which extends through and is secured to the wall 2. The upper open end of the pipe 37 is normally closed against the escape of gas by means of a cap comprising a tube 40 extending down over the pipe a suitable distance, the tube having a head 41 closing its upper end, the lower end of the tube having a cylindrical shaped screen 41 secured thereto and extending about the pipe 37, the cap being elevated by means of a chain 43 connected thereto when the gas is generated in excess of requirements.

A gas-bell comprises a cylindrical shell 44 of suitable diameter to freely pass over the wall of the tank and within the casing 3, the lower end of the bell being open and im-

mersed in water, as is customary in gas generators, the shell having a conical top 45 into the middle portion of which extends a cylindrical magazine for holding the carbid, the magazine having a hopper shaped bottom 47 and a top 48, the top being provided with a removable filling plug 49.

The exterior of the upper portion of the casing 3 is provided with two sockets 50 and 51 into which two guide-bars 52 and 53 are removably inserted, upper ends of the guide-bars being held the required distance apart by means of a connecting cross-bar 54. The top 45 has two brackets 55 and 56 thereon in which guide rollers 57 and 58 are mounted respectively and are normally in contact with the guide-bars.

The feeding apparatus comprises a valve box which has two upright side plates 59 and 60, of suitable length, which are connected at their upper ends to the lower open end of the hopper bottom 47, and two relatively short plates 61 and 62 connected also to the bottom 47 and to the plates 59 and 60. The plates form a rectangular discharge chute 63 through which the carbid falls into the tank. The plates 59 and 60 have extensions 64 and 65 on their lower portions respectively and the ends of the extensions have downwardly extending ears 66 and 67 respectively, provided respectively with pivots 68. The plates 59 and 60 are maintained in parallel relation by means of thimbles 69 and tie-rods 70. Two pivot rods 71 and 72 are supported in the two plates 59 and 60 and extend from one to the other of the plates at a suitable distance below the plane of the lower end of the plates 61 and 62 and somewhat farther apart than the space between the plates 61 and 62. Two valve bodies 73 and 74 are mounted respectively on the pivots 71 and 72 between the side plates 59 and 60 and extend upward to the lower ends of the plates 61 and 62, the valves having curved upper working faces 75 and 76 respectively, which are adapted to close the chute or partially open it. The valve bodies are provided at the upper portions thereof with pivot rods 77 and 78 respectively, two stiff links 79 and 80 being connected to the rod 77, two similar links 81 and 82 being connected to the rod 78. The two plates 59 and 60 have vertical guide slots 83 and 84 therein, respectively, midway between the pivots 71 and 72. A pivot rod 85 extends through and is guided in the two guide slots and is connected with all the links, and two operating rods 86 and 87 are connected at one end to the pivot rod 85.

An operating lever comprises two arms 88 and 89 connected at one end to the pivot 68, and a cross bar 90 connected to the opposite end of the arms. A pivot rod 91 is connected to the arms of the lever and also to the normally lower ends of the rods 86 and 87.

87. A thimble 92 is preferably placed between the two arms of the lever and secured thereto by a tie-rod 93 so that the lever may be stopped in its upward movement by the 5 thimble coming in contact with the lower edges of the side plates 59 and 60 in which position the valve is wide-open. A weight 94 is suitably secured to the two arms 88 and 89 of the lever adjacent to the cross bar 90 for normally holding the lever down with the valve in closed position, the movement 10 of the pivot rod 85 downward causing the links connected therewith to draw the valve bodies each to the other.
- 15 In order to prevent the carbid from packing on the bottom of the magazine a suitable number of standards 95 are secured upon the bottom 47 and support a cone 96 at a suitable distance above the bottom.
- 20 In some cases the bell is provided with a weight 97 on its lower end composed of lead in order to maintain the desired degree of pressure on the gas.

In practical use the generating tank contains a suitable quantity of water as does also the sealing compartment, and normally the cross bar 28 is depressed. The plug 49 is removed while the magazine is being filled and refilled with carbid, while the 30 feed valve is closed. If it is desired to feed a quantity of carbid by hand or quickly generate the gas, the attendant raises the handle 23 and again pushes it down or may hold it up by means of the arm 24. When 35 the volume of gas generated is sufficient to elevate the bell to the desired extent the operating lever is carried away from the cross bar 28 and permits the feed valve to close, the cross bar being arranged at a suitable height. When the gas is drawn off by 40 the burner the bell descends until the operating lever, comprising the arms 88 and 89, again comes in contact with the cross bar 28 so as to arrest the downward movement of the free end of the lever while the bell 45 continues to descend and causes the feed valve to open and discharge more carbid which falls into the water and generates sufficient gas to again force the bell upward, and such operations are repeated automatically 50 until the carbid has been fed from the magazine. The residuum and foul water may be withdrawn without disturbing the operation of the apparatus if the water is instantly replaced by fresh water poured 55 into the funnel 9. When the bell rises as far as desired and there is an excess of gas being generated, the bell pulls on the chain 43 and raises the cap tube 40 above the top 60 of the water level in the tank and permits the excess gas to pass through the screen 42 and thence out of the pipe 39, the screen preventing scum from being carried out from the surface of the water.

Having thus described the invention, what 65 is claimed as new is—

1. Feeding means including a valve box 70 that is rectangular in cross-section, two valves pivotally supported below two opposite wall portions respectively of the box 70 and extending upward approximately to the wall portions and also each toward the other, a movably guided pivot rod, two links 75 pivotally connected to the rod and to the outer upper portion of one of the valves on opposite sides thereof and two links connected also to the rod and to the outer upper portion of the remaining one of the valves on opposite sides thereof for forcing the 80 valves together.

2. Feeding means including a vertically movable valve box comprising two long sides having each a vertical guide slot therein and two relatively shorter sides, the long sides having rear extensions respectively, 85 two valves pivoted to the two long sides and movable between them under the shorter sides, each valve to or from the other, a pivot rod extending movably through the guide slots of the two sides and through 90 the valve box, two links connected to the rod and to one of the valves, two links connected also to the rod and to the remaining one of the valves, two operating rods connected to opposite end portions of the pivot 95 rod, an operating lever pivoted at one end to the extensions of the long sides and connected to the operating rods, a weight secured to the opposite end portion of the lever for forcibly closing the valves, and a 100 device supported below the weighted portion of the lever to which the lever is periodically carried by the moving valve box for actuating the lever to open the valves.

3. In carbid-feeding means, the combination of a valve box that is rectangular in cross-section, two opposite wall portions thereof being longer than the remaining two wall portions and having rear extensions, two valves pivotally supported between the 110 two longer wall portions and extending to the near ends of the shorter wall portions, a lever comprising two bars pivoted at one end to the extensions of the two wall portions respectively, two operating rods pivotally 115 connected to the two bars of the lever respectively, a pivot rod connected to the two operating rods, two links connected to the pivot rod and to one of the valves, and two links connected also to the pivot rod and to 120 the remaining one of the valves.

4. In an acetylene gas generator, carbid feeding means comprising a magazine movably guided vertically, means for moving the magazine, a valve box that is rectangular 125 in cross-section connected to the magazine and carried thereby, two opposite wall portions of the box being longer than the re-

maining two wall portions and having each a rear extension thereon, two valves pivotally supported between the two longer wall portions and extending to the near ends 5 of the shorter wall portions, the valves having curved ends opposite to said ends of the wall portions; a lever comprising two bars pivoted at one end to the extension of the two wall portions respectively and a weight 10 secured between the opposite ends of the two bars, means operatively connecting the

lever to the two valves, and an adjustably supported device below the weighted portion of the lever in the path of movement of the lever.

15

In testimony whereof, we affix our signatures in presence of two witnesses.
